SOUND RANGING SYSTEM

Application filed July 16, 1928. Serial No. 293,228.

My invention relates to a method for and a system in which a variable retardation of electric currents is effected and has particular reference to the application of the above 5 method and system in sound ranging systems. Sound ranging is the determination of the direction from which a sound is coming in whatever medium it may happen to be traveling. Such systems, as a rule, operate on the 10 principle of binaural compensation.

To locate the direction or range of a sound, living creatures including human beings, as a rule, turn their heads in such a way that their ears are substantially equi-distant from 15 the source of sound. If one ear is farther from the source of sound than the other, the impulses in the farther ear will be translated into conscious impulses later than those from the other ear and thus the sound images will 20 be binaurally off-center. Unconsciously the creature or person turns his head so that the difference in time is decreased to zero, making the line joining the two ears perpendicular to the direction of the oncoming sound.

25 Systems have been arranged working on substantially the same principle wherein a pair of sound receiving instruments, either mechanical or electrical, have been disposed in a medium, commonly air or water, for the 30 ranging of sound. By suitably connecting the sound receiving instruments to the ears of a person so that oncoming impulses from each of the receiving instruments will be conducted to the ears of a person, it is possible 35 to range a sound by turning the two receiving instruments together and thus centering the images. Such systems have been unsatisfactory for the reason that they are cumbersome and are not susceptible of convenient 40 manipulation.

Another system for ranging sound employs the idea of having acoustic paths from the sound receiving instruments to the listener or observer of different effective lengths. Al- 45 though it is possible to build a non-electrical system of this kind, its greatest application has been in electrical systems.

50 It is to be understood that all these systems have the same psychological basis for their operation, i. e. binaural centering of the sound

images. Although this binaural centering of two sound images from a common sound source involves synchronization, it is distinctly different from ordinary synchronization. Thus for example the ordinary person can not resolve two sounds that reach his ears at a smaller time interval than one one-hundredth of a second. Such closely timed sounds will appear as continuous to the person. However, when ranging sound, the ordinary person can determine the direction of sound travel to a degree corresponding to one one-hundred thousandth of a second difference in time of arrival between the impulses at the two ears. Hence it is obvious that the binaural centering of two sound images from one sound source, really a synchronization of two images from a common source, is fundamentally different from ordinary synchronization of separate sounds. 55 In sound ranging systems, it is the binaural centering faculty which is made use of. The variation in the length of acoustic paths from the sound collectors or pickups to the ears of the operator merely cause a virtual binaural centering of the sound images. By equating the virtual centering action with the actual physical accentricity of the sound source to the sound collectors, it is possible to directly determine the true direction of sound travel. 60

Sound ranging systems of the electrical variety and employing the principle of an artificial lag or binaural compensation are substantially as follows. A pair of sound receiving instruments or pickups is disposed in the medium in which the sound is traveling at a predetermined distance apart from each other and preferably facing in the same direction. These pickups, although of various types, are usually microphones. Connecting the two microphones is an artificial retardation or lag line composed of a plurality of low pass filter sections. Each section of such a line is usually composed of an inductance unit and a capacity unit, the inductance unit being adapted to be in series with the line, while the capacity unit is across the line. A complete lag line of this character usually comprises a plurality of inductance units connected in series and a plurality 65 70 75 80 85 90 95 100

of capacity units connected at the junctions of the inductance units across the line. Such a line has the property of delaying an electric wave without substantially changing the phase relationship between the current and the voltage.

The value of the retardation of the entire line connecting the sound receiving instruments is usually equal to the time interval 10 within which a sound impulse could travel the distance separating the sound receiving instruments in the medium considered. To use such a system, it is customary to sever the retardation line at any one of the inductance unit junctions. A telephone receiver is thereupon placed across the line on one side of this break while another receiver is similarly connected on the other side of the break. The result is that each sound receiving instrument has a predetermined amount of lag line connected between it and its corresponding telephone receiver, the two portions of the lag line being complementary to each other. By severing the lag line at 15 any one of the various junctions of the inductance units, it is possible to distribute variable portions to each part of the system. In this way, it is possible to artificially compensate in the electrical lag line for the 20 unequal arrival of sound impulses at the two receiving instruments and thus obtain, by this compensation, binaurally centered impulses at the receivers. By calibrating the 25 point of severance of the lag line with respect to each end of the line, it is possible to directly read off in degrees the angle between the base line and the direction of travel of the sound waves. An operator listening at the two telephones can thus 30 arrange the complementary portions of the lag line so that the impulses in the telephones will be synchronized, thus binaurally centering the sound images.

To sever the line at any one of a number 45 of inductance unit junctions and connect a telephone receiver to the lag line on each side of the break, requires a very complicated system of switching, both with regard to the electrical and mechanical features. Although in order to simplify the switching 50 problem, the lag line may be composed of a small number of sections, each section having a high unit value, certain undesirable factors enter in when this is done. If the sections are made large in value, the operation 55 of the lag line is fundamentally affected in an undesirable manner. The cut-off frequency of the lag line, which is at the same time a low pass filter, becomes so low that 60 the utility of the system becomes restricted to signals in which extremely low frequencies are used. Furthermore, the only place at 65 which the line may be severed is at the junction points of each section, that is, across each condenser. It is manifest that if large

sections are to be cut in and out as units, it will be impossible to obtain any more than a very coarse variation of length of lag line.

Since the variation in the length of lag line corresponds in a physical sense to a 70 change in the direction of sound, it is equivalent to dividing up the angular range in which the device will operate into an arbitrary number of possible directions with no intermediate values. Electrically, any reading, intermediate indications, is impossible 75 since there is no correspondence between the position of the indicator and connections in the system.

In order to obtain a high degree of accuracy in sound ranging, it is customary to increase the number of sections composing the lag line, making each section of smaller unit value. The switching problem along with the complexity of wiring and number of 80 junction points, becomes enormously increased, making an accurate system of this kind very complicated and expensive. Furthermore, even in such a system, however small each section of the lag line might be 85 made, it is still necessary to make distinct jumps from one section to another. Although much finer readings are possible, interpolation between readings is just as impossible and just as meaningless as in a less complicated and cruder system.

An object of my invention is to devise a lag line, the effects of which can be varied to as fine a degree as may be desired. Other objects are to effect such variation in lag line 100 in a smooth, gradual, and uninterrupted manner, and to obtain such variation without any accompanying complexity of switching or connections. Further objects are to incorporate such a lag line in a system such as for 105 ranging sound; to make such a system smoothly and uninterruptedly operable over its entire range; to allow of interpolation between any two dial indications; and to devise a sound ranging system of this character 110 which will be simple, inexpensive, and easy to operate.

In general, my improved lag line is composed of a nominal number of ordinary filter sections of well known construction. These 115 need not necessarily be of equal lag value. In order to uninterruptedly vary the effective length of the line, I obtain currents at potentials corresponding to the potential in any desired portion of the lag line. Inasmuch 120 as the degree of retardation or lag suffered by electrical waves in the line is strictly proportional to the amount of line traversed, it can be seen that the currents obtained, corresponding to the desired potentials, will have 125 any desired degree of retardation compared to the original currents and potentials at the input side of the lag line.

To obtain such potentials, I dispose a pick-up coil in inductive relationship to any de- 130

sired inductive units or portion thereof of the lag line. The electrical potentials induced in this pickup coil, by virtue of the several current impulses in the inductance units coupled

thereto, have of course, definite lags with respect to the electrical impulses entering the initial input section of the line. The net or summation potential induced in the pickup coil will then have a definite lag with respect to the impulses entering the input of the line which lag may be considered as the vectorial summation of the several lags corresponding to the impulses traversing the individual inductively-coupled inductance units.

By arranging the inductance units and coil in such a manner that selective cooperation may be obtained between the coil and any portion of the inductance part of the lag line, it is possible to obtain any desired retardation within the range of the entire lag line. If now the pickup coil is so moved with reference to the lag line that it comes into closer inductive relationship with inductance units ahead in the direction of motion and at the same time reduces its inductive relationship with the inductance units in a direction opposite to its motion, then the net induced potential in the pickup coil will have a time lag with respect to the input of the lag line, which lag will increase or decrease as the case may be, not by discrete discontinuous intervals but in a perfectly continuous, uniform and uninterrupted manner. The lag of this net induced potential will, of course, change by an amount equal to the lag of the closest associated section of the line when the pickup coil has been displaced a distance corresponding to the physical dimensions of said section. In this manner the lag of the net induced potential corresponding to any position of the pickup coil may be determined from said position of the coil and the constants of the associated lag line.

Due to the interplay of the capacitance and inductance on electrical waves, the gradual variation in length along the inductive portion of the lag line has an effect on the effective length of the capacitative portion of the lag line. The mere fact that a variation in effective length of less than the value of one inductive unit is made, does not indicate that the capacitative portion of the system remains unchanged. Each inductance unit may be considered as a connecting link between adjacent capacitative units and change of the effective length of the inductance portion of the line from a point just in advance of the junction point where the capacitative unit is connected to a point just beyond this junction point, does not cause any sharp variation in the effective length of the line. Hence, while physically only the inductive portion of the lag line is varied, electrically, the capacitative portion

of the lag line is also varied in the same uninterrupted manner because of the interaction between the two portions of the lag line.

In order to obtain real precision in the alteration of the effective length of the lag line, it is highly desirable that no nodal points exist within the line. Such points are caused by reflected waves interfering with the oncoming waves and causing so called standing waves. In order to eliminate any such possibility, I preferably avoid having any sharp electrical discontinuity in the line. At the end of the lag line, I dispose a terminal characteristic impedance of any kind whatsoever. As is well known, such an impedance has a value equal to the value of the line facing it. Within this impedance all the electrical energy coming through the line is absorbed without reflection.

If the coil which is in inductive relationship to the inductance units of the lag line, were allowed to have secondary currents therein induced by the currents in the inductance portion of the lag line with which it cooperates, it is obvious that there would be highly undesirable transformer action. If this pickup coil were allowed to absorb energy from the lag line, it would constitute a marked departure at that portion of the line from the ordinary characteristics of the line and result in reflected waves or ripples being sent out to both ends of the line. In order to avoid such undesirable possibility, I preferably arrange so that the potentials induced in the coil set up potentials in another circuit in which currents may flow without reacting on the coil. To obtain this, I preferably couple the coil to the input side of a vacuum tube amplifier. By properly biasing the grid of the amplifier, it is possible to obtain output amplified potentials and currents without having any appreciable current flowing in the pickup coil. In this way, it will be seen that original impulses incoming into the lag line will be dissipated, but at any desired degree of retardation, may give rise to potentials which in turn give rise to currents.

In order to apply such a lag line to a sound ranging system, I preferably dispose a complete lag line in operative relationship to each of the two sound collecting or receiving instruments commonly known as pickups. Preferably the lag lines are equal in length or retardation value, each one having a retardation value somewhat equal to the time which a sound impulse takes to travel between the two sound collecting instruments in the medium desired. Each of the lag lines has its pickup or secondary coil in variable relationship to the inductive portions of said lines. Each of said coils is connected to a suitably biased thermionic amplifier, the outputs of which go to indicating means such

as telephones. The net time lag between the responses of the two indicating instruments will depend upon the time lag in the excitation of the sound receiving instruments and 5 the compensating lag in the effective portions of the two lines. It is evident that the difference in the value of the effective lengths of the lag lines will determine the compensation of the current impulses.

10 By suitable mechanical means, I arrange the two coils so that their positions are simultaneously and correspondingly changed, but in an opposite sense with respect to each of the lag lines. Thus as one coil is at the input 15 end of the lag line, the other coil is at the terminal impedance end of its line. Then as the first coil moves away from the input end of the line and toward the impedance, the other coil moves away from the impedance 20 of its line and toward the input end. At the center of the lines, the coils will be in the same position on the lag line and there will be no net compensatory lag introduced. Such a position of the coils will correspond 25 to a direction of sound perpendicular to the line joining the sound receiving instruments.

The mechanical means actuating both coils simultaneously may be suitably arranged to actuate any desired indicating means. Such 30 means may be calibrated in any terms desired and usually would be calibrated in terms of degrees giving the angle between the direction of sound travel and the base line at the sound receiving instruments. It is evident 35 that the indications may be made as close or as far apart as may be found desirable since interpolations between indications are possible.

Although such a sound ranging system may 40 be read to as fine a degree as may be found desirable, the simplicity of the system as well as expense are practically independent of the precision, except for ordinary factors like workmanship and care in the manufacture.

45 In another aspect of my invention, the variable line may be considered as a low pass filter whose cut off slope may be gradually and smoothly varied from a gentle taper to a sharp fall. In filters of this kind, as sections of like character are added, the cut-off of the filter tends to become much more sharp and critical by definite steps. For some purposes, it may be desirable to gradually vary the slope of the cut-off by varying the effective 50 length of the filter. Of course the original currents through the filter will be dissipated but currents having the desired properties will appear at the output of the amplifier. The sections of the filter need not 55 necessarily be of similar character and might be so designed as to actually vary the cut-off frequency. In such a case, it is possible to obtain a smooth and gradual variation of the cut-off frequency.

60 65 Although I have disclosed my improved

lag line in conjunction with a sound ranging system, its field of utility is in no way to be circumscribed thereby. Thus it is possible and may be found desirable in the recording and reproduction of sound to introduce echo effects and this may be accomplished by 70 means of my improved lag line to any desired degree. Another field to which my invention may be applied is in radio direction finders or radio ranging systems. It is obviously possible to replace the spaced pickups 75 by spaced radio receiving systems. Other applications of the lag line will occur to those skilled in the art, all of which are within the scope of my invention.

80 Referring to the drawings, Figure 1 is a diagrammatic showing of my invention as applied to a sound ranging system;

85 Figure 2 shows a mechanical embodiment of the diagrammatic showing of Figure 1;

90 Figure 3 is a modification.

95 Referring to Figure 1, 1 and 2 are sound receivers of any type whatever, such as microphones, and adapted to translate sound impulses into electrical impulses. These receivers as used generally are so disposed that they can pick up sound impulses traveling through water or air, and are separated by a predetermined distance. Battery 3 energizes the microphones, the circuits of which are completed through the primaries of transformers 4 and 5. The use of transformers at these points is optional.

100 The secondaries of these transformers are connected to artificial lag lines 6 and 7 respectively. These lines are composed of inductance units 8 connected in series on one side of the line and so disposed in this instance that there is the proper amount of mutual inductance between adjacent units. Condensers 9 are connected from the junctions of adjacent coils across to the other side of the line, which may be composed of 105 as many sections as may be found desirable. Across the further end of each line is connected a terminal characteristic impedance or network 10, the value of which is such that the impedance at the terminals of 10 looking either way, is the same. In this way, 110 electrical impulses starting in transformers 4 and 5 go down the lines, being retarded therein and are eventually entirely absorbed in impedances 10. The absorption is such that no reflections occur.

115 In inductive relation to the inductance units 8 of artificial lines 6 and 7, are pickup coils 11 and 12. These coils are connected respectively to the grids of vacuum tubes 17 and 18. The other ends of the coils are connected through biasing batteries 13 and 14 to a common return 19 to the filaments of the tubes, thereby completing the grid circuits. Battery 20 is a common plate supply 120 for the two tubes and is connected to the plate of each of the tubes through conductors 125

tors 21 and 22 and primaries of transformers 23 and 24. If desired, individual plate batteries may be used for each tube. The secondaries of transformers 23 and 24 are coupled to an indicating means, here shown as telephones 75 and 76 by leads 77 and 78. Across the secondaries of transformers 23 and 24 is conductor 90 with switch 79. Joining the point between telephones 75 and 76 and between the two secondaries of transformers 23 and 24 is conductor 91 with switch 80. The reasons for the presence of the switches and cross connections will appear later.

5 Coils 11 and 12 are gradually movable from one end of the line to the other. The arrangement is such that as coil 11 moves toward impedance 10 of line 7, coil 12 moves away from impedance 10 of line 6. Artificial lines 6 and 7 are preferably of equal value. The time lag value of lines 6 and 7 is such that the retardation suffered by electric currents through the entire line is somewhat greater than the time taken for sound waves 25 to travel the distance between microphones 1 and 2 in the medium.

The operation of the system is as follows:— Assume a source of sound directly in front of microphones 1 and 2 and equally distant 30 therefrom. Sound impulses will arrive simultaneously at microphones 1 and 2. These simultaneous impulses will be translated into simultaneous electrical impulses at transformers 4 and 5. The outputs of the two 35 transformers will start out down the artificial lines at the same instant. The impulses from transformer 4 will go down the entire length of line 6 and suffer the maximum time lag before coil 12 will be affected. The current impulses in the last sections of line 6 will induce an electro-motive force in coil 12. By biasing the grid of tube 18 with a battery 14 of suitable value, it is possible to prevent any current from flowing in coil 12, thus eliminating 40 the absorption of any energy from the lag line. The potential impulses induced in 12 affect the grid of tube 18 and give rise to current impulses through primary of transformer 24. Induced impulses in the second- 45 ary go through lead 78, through telephone 76, switch 80, lead 91. Thus the impulses in telephone 76 are delayed by nearly the full lag of line 6 with reference to the microphone 2.

55 Impulses from transformer 5 starting down line 7 immediately induce an electro-motive force in coil 11. Although the impulses from transformer 5 travel down the entire length of 7 and are entirely absorbed 60 in impedance 10, the pulsating current affects coil 11 before any considerable time lag has been suffered. Coil 11 is operated similarly to coil 12 and without having any current in it, affects the grid of tube 7, and finally causes 65 current impulses through telephone 75. The

result is that impulses due to coil 11 will arrive at telephone 75 sooner than impulses due to 12 will arrive at telephone 76. The difference between these artificial lags will be approximately equal to the time lag suffered by the sound waves traveling the distance between the pickups through the medium. The listener at telephones 75 and 76 will thus be audibly warned that coils 11 and 12 are not correctly positioned since the sounds in the 70 telephones are not synchronous and the sound image will be binaurally off center. He will, therefore, in the case cited, operate coils 11 and 12 so that one or both will approach electrically identical points on each line, where- 75 by the sounds will become synchronous, because the artificial lags will then be equal, that is, the compensating lag will be zero. By suitably calibrating the positions of coils 11 and 12 with respect to the end positions as 80 shown, it is possible to directly read off the angle between the line joining microphones 1 and 2 and the direction of travel of sound in the medium.

To cause the sound impulses to arrive at 85 telephones 75 and 76 at the same instant, that is, to obtain an exact binaural centering of the image of the sound source, coils 11 and 12 may be moved as little as may be found desirable. Since the pick-up coils 11 and 12 of 90 each of the lines are so related to the lag lines that there is mutual induction between them and several inductive units of the respective line, it is impossible for coils 11 and 12 to undergo any sharp and discontinuous variation 95 in the effective potentials induced therein. Thus the gradual change of position of the coils 11 or 12 with respect to the inductive portions of the lag line results in a smooth 100 and uninterrupted change in the effective lag between the microphone 1 and telephone receiver 75 and between microphone 2 and telephone receiver 76.

105 Referring to Figure 2, the inductance units of the lag lines, coils 8, are disposed in insulating tubes 25. The coils are separated by 110 spacing blocks 36 to give the desired amount of mutual induction. An axial channel allows connecting wires from the junctions of coils 8 to come out in a cable 26 for connection to a panel 27. A group of condensers 9 forming the capacity units of the line are 115 properly connected to panel 27 so that the artificial line is finally connected as shown in Figure 1. Around the outside of tubes 25 are pickup coils 11 and 12 wound on suitable forms and adapted to slide the length of tubes 25. As shown, these pickup coils are longer than the length of any one inductance unit and preferably are long enough so that they include portions of each of the adjacent units. In this instance, coils 11 and 12 are 120 long enough to cover three of coils 8.

125 Tubes 25 are suitably mounted in a frame 130 35. This frame supports two sprocket

wheels 32 and 33 connected by an endless sprocket chain 31. The chain is affixed to movable coils 11 and 12 by suitable means 30 so that as the chain moves, the coils 11 and 12 move with it. The coils are connected to proper points on the chain so that by turning sprockets 32 and 33, coil 11 will go one way and coil 12 will go the other way. By suitably connecting the shaft of sprocket 32 or 33 to a suitable indicating dial, the angle between the direction of sound travel and the microphone baseline may readily be read off. Coils 11 and 12 are connected by flexible leads 37 to batteries and tubes as shown in Figure 1.

Figure 3 shows a slightly modified form. As is obvious from Figure 1, it is possible to reverse one of the artificial lines so that pickup coils 11 and 12 may travel in the same direction instead of in opposite directions. The artificial lag lines are reversed so that coils 11 and 12 are connected by cross arm 40 and may slide together. This sliding may be suitably effected by sprocket chain 42 connecting cross arm 40 at 41 and suitably actuated by sprockets 43 and 44. The whole device is mounted in a frame 50. Sprockets 43 or 44 may actuate an indicator or a dial so that angles may be directly read off.

Thus far the system has been assumed to be connected as shown in Figure 1. However, by suitably operating switches 79 and 80, the system may be made to operate so that instead of synchronizing impulses, or binaurally centering continuous impulses, the setting of the pickup coils may be made with the object of obtaining a maximum or minimum amount of sound. If switch 79 is closed while switch 80 remains closed, conductors 77 and 78 will always be at the same potential. The net result of this will be that whatever displacement of sounds there might normally be between telephones 75 and 76, will be eliminated and the same sounds will issue from both telephones simultaneously. The sound issuing from both telephones will now be a vectorial summation of the energies in transformers 23 and 24 and will represent an averaging, rather than a separation, as before. It is evident that, if the net compensation in the lag lines is equal and opposite to the difference in arrival of the sound impulses at the pickups, the sound impulses issuing from telephones 75 and 76 will be exactly in phase and at a maximum. This is because the phase difference having been reduced to zero, the addition becomes merely arithmetical and results in a maximum absolute value. At this point, the setting of the pickup coils will correspond to a binaural centering of the images of sound before and the direction of sound will be determined.

If switches 79 and 80 are both open, the outputs of transformers 23 and 24 will be in opposition through telephones 75 and 76. If

the pickup coils are properly positioned with a given direction of sound travel, then telephones 75 and 76 will be silent. This is because the two outputs are in direct opposition and the summation reduces to mere arithmetical subtraction, resulting in a minimum absolute value. It is perfectly obvious that this same result may be obtained by having both switches 79 and 80 closed, as above, and reversing the polarity of one of the pickup coils.

Although I have shown the inductance units of the artificial lines as mounted in a straight line, it is obvious that they may be bent into a circular shape, forming a toroidal structure. Coils 8 might also have their axes radial as the coils of a generator. The secondary coils could then be mounted similar to the rotor coils of a generator. My invention is in nowise limited in the disposition of the elements of the lag lines or to the mechanical means employed for moving the pickup coils or recording the motion thereof.

What is claimed is:—

1. A sound ranging system comprising a plurality of pickups adapted to translate sound impulses into electrical impulses, means for translating electrical impulses into sound energy, an artificial line composed of inductance and capacity units interconnected intermediate said pickups and said translating means, and means inductively associated with inductance units of said artificial line for uninterruptedly varying the effective length of said artificial line, said inductively associated means including means for keeping the current in the inductively associated means at a negligible value, whereby any distortion in the inductance units of said line due to the presence of said inductively associated means is prevented.

2. A sound ranging system comprising a plurality of pickups adapted to translate sound impulses into electrical impulses, means for translating electrical impulses into sound impulses, an artificial line composed of interconnected inductance and capacity units intermediate said pickups and translating means, means inductively associated with the inductance units of the artificial line, said inductively associated means being connected to the translating means, said connections including a vacuum tube so biased that no appreciable input current is required, for preventing any appreciable distortion in the inductance units of said line due to the presence of said inductively associated means and means for changing the inductance units of the artificial line with which said inductively associated means operates.

3. A sound ranging system comprising a pair of pickups adapted to translate sound impulses into electrical impulses, a pair of equal and separate artificial lines, means for

generating impulses in said lines corresponding to outputs of said pickups, means for translating electrical impulses into sound impulses, electro-magnetic coupling means between said lines and said translating means and means for keeping the current in said coupling means at a negligible value.

4. In a sound ranging system, an artificial line comprising a plurality of interconnected inductance and capacity units, said inductance units being so arranged that there is mutual inductance between adjacent units, a coil in inductive relation to the inductance units of said line, and means for keeping the current in the coil at a negligible value.

5. An artificial line comprising inductance and capacity units connected together, means inductively associated with predetermined portions of the inductive portion of the line for uninterruptedly varying the effective lag value of the line, said means including means for keeping the current in said inductively associated means at a negligible value.

6. An artificial line comprising inductance and capacity units connected together and adapted to retard electric currents, means for obtaining potentials corresponding to currents within said line and having any desired degree of retardation within the range of said entire line while keeping the current in the said means at a negligible value, and means for obtaining currents corresponding to said potentials.

7. An artificial line comprising inductance and capacity units connected together and adapted to retard electric currents, a terminal characteristic impedance at one end of said line, means for obtaining potentials corresponding to currents within said line and having any desired degree of retardation within the range of said entire line and while keeping the current in the said means at a negligible value, means for obtaining currents corresponding to said potentials.

8. A retardation system comprising a plurality of inductance and capacity units connected together to form an artificial line, a characteristic impedance at the end of said line, a coil associated with predetermined inductance units, and a thermionic amplifier connected to said coil, said amplifier being so adjusted that it functions substantially as a potential amplifier only.

9. An electric system comprising a plurality of pickups adapted to translate sound impulses into electrical impulses, means for translating electrical impulses into sound impulses, an artificial line composed of inductance and capacity units interconnected intermediate said pickups and translating means, means inductively associated to cooperate with more than one of said inductance units at one time, said inductively associated means being connected to the translating means, said connections including means for

keeping the current in the inductively associated means at a negligible value, and means for changing the inductance units of the artificial line with which said inductively associated means cooperates.

10. An electric system comprising a plurality of pickups adapted to translate sound impulses into electrical impulses, means for translating electrical impulses into sound impulses, an artificial line associated with each of said pickups, said artificial line having a dead end composed of a terminal characteristic impedance, and means inductively associated with the inductance units of said line, said inductively associated means being connected to the translating means, and said connections including means for keeping the current in the inductively associated means at a negligible value.

11. An electric system having, in combination, two sound pickup devices, means for translating the sound impulses picked up by each pickup device into electrical impulses, lag lines interconnected intermediate the pickup devices and the translating means, means inductively associated with each lag line for picking up voltage impulses from the corresponding lag line, means for uninterruptedly varying the effective value of the corresponding lag line in order gradually and smoothly to retard the voltage impulses picked up from the corresponding lag line, means whereby the inductively associated means draws a negligible amount of energy from the lag lines, a circuit connected with each inductively associated means, and means for making the retarded impulses manifest in the two last-named circuits.

12. An electric system having, in combination, two sound pickup devices, means for translating the sound impulses picked up by each pickup device into electrical impulses, lag lines interconnected intermediate the pickup devices and the translating means, each lag line having a plurality of inductor coils, a pickup coil for each lag line adapted to be moved relatively to the inductor coils of the corresponding lag line, whereby adjacently disposed inductor coils of each lag line serve successively as primary coils and the corresponding pickup coil serves as the secondary coil of a transformer to cause each pickup coil to pick up voltage impulses from its corresponding lag line, means for continuously moving relatively the inductor coils and the corresponding pickup coil of each lag line to vary uninterruptedly the effective value of the corresponding lag line in order gradually and smoothly to retard the voltage impulses picked up from the corresponding lag line, each lag line having a terminal characteristic impedance for maintaining the impedance of the corresponding lag line constant in order to prevent reflections of current waves within the lag lines, two vacuum

tubes each having an input circuit and an output circuit, means for biasing the vacuum tubes to keep the current flow in the input circuits at a negligible value, and means for connecting the pickup coils with the respective input circuits, whereby the retarded impulses are made manifest in the output circuits.

13. An electric system having, in combination, two sound pickup devices, means for translating the sound impulses picked up by each pickup device into electrical impulses, lag lines interconnected intermediate the pickup devices and the translating means, means inductively associated with each lag line for picking up voltage impulses from the corresponding lag line, means for uninterruptedly varying the effective value of the corresponding lag line in order gradually and smoothly to retard the voltage impulses picked up from the corresponding lag line, two vacuum tubes each having an input circuit and an output circuit, means for biasing the vacuum tubes to keep the current flow in the input circuits at a negligible value, and means for connecting the inductively associated means in the respective input circuits, whereby the retarded impulses are made manifest in the output circuits.

14. An electric system having, in combination, two sound pickup devices, means for translating the sound impulses picked up by each pickup device into electrical impulses, lag lines interconnected intermediate the pickup devices and the translating means, each lag line having a plurality of inductor coils, a pickup coil for each lag line adapted to be moved relatively to the inductor coils of the corresponding lag line, whereby adjacently disposed inductor coils of each lag line serve successively as primary coils and the corresponding pickup coil serves as the secondary coil of a transformer to cause each pickup coil to pick up voltage impulses from its corresponding lag line, means for continuously moving relatively the inductor coils and the pickup coil of each lag line to vary uninterruptedly the effective value of the corresponding lag line in order gradually and smoothly to retard the voltage impulses picked up from the corresponding lag line, two vacuum tubes each having an input circuit and an output circuit, means for biasing the vacuum tubes to keep the current flow in the input circuits at a negligible value, and means for connecting the pickup coils with the respective input circuits, whereby the retarded impulses are made manifest in the output circuits.

15. An electric system having, in combination, two lag lines, means for obtaining electrical currents in each lag line, means inductively associated with each lag line for picking up voltage impulses from the corresponding lag line, means for uninterruptedly vary-

ing the effective value of the corresponding lag line in order gradually and smoothly to retard the voltage impulses picked up from the corresponding lag line, means whereby the inductively associated means draws a negligible amount of energy from the lag lines, a circuit connected with each inductively associated means, and means for making the retarded impulses manifest in the two last-named circuits.

16. An electric system having, in combination, two lag lines, means for obtaining electrical currents in each lag line, each lag line having a plurality of inductor coils, a pickup coil for each lag line adapted to be moved relatively to the inductor coils of the corresponding lag line, whereby adjacently disposed inductor coils of each lag line serve successively as primary coils and the corresponding pickup coil serves as the secondary coils of a transformer to cause each pickup coil to pick up voltage impulses from its corresponding lag line, means for continuously moving relatively the inductor coils and the corresponding pickup coil of each lag line to vary uninterruptedly the effective value of the corresponding lag line in order gradually and smoothly to retard the voltage impulses picked up from the corresponding lag line, each lag line having a terminal characteristic impedance for maintaining the impedance of the corresponding lag line constant in order to prevent reflections of current waves within the lag lines, two vacuum tubes each having an input circuit and an output circuit, means for biasing the vacuum tubes to keep the current flow in the input circuits at a negligible value, and means for connecting the pickup coils with the respective input circuits, whereby the retarded impulses are made manifest in the output circuits.

17. An electric system having, in combination, two lag lines, means for obtaining electrical currents in each lag line, means inductively associated with each lag line for picking up voltage impulses from the corresponding lag line, means for uninterruptedly varying the effective value of the corresponding lag line in order gradually and smoothly to retard the voltage impulses picked up from the corresponding lag line, two vacuum tubes each having an input circuit and an output circuit, means for biasing the vacuum tubes to keep the current flow in the input circuits at a negligible value, and means for connecting the inductively associated means in the respective input circuits, whereby the retarded impulses are made manifest in the output circuits.

In testimony whereof, I have signed my name to this specification this 13th day of July, 1928.

HORATIO W. LAMSON.

CERTIFICATE OF CORRECTION.

Patent No. 1,874,196.

August 30, 1932.

HORATIO W. LAMSON.

It is hereby certified that error appears in the printed specification of the above-numbered patent requiring correction as follows: Page 1, line 78, for "accentricity" read "eccentricity"; page 2, line 118, for "lngh" read "length"; page 5, line 64, for "7" read "17"; page 7, line 41, claim 7, strike out the word "and", and insert the same before "means" in line 43; page 8, line 86, claim 16, for "coils" read "coil"; and that the said Letters Patent should be read with these corrections therein that the same may conform to the record of the case in the Patent Office.

Signed and sealed this 29th day of November, A. D. 1932.

(Seal)

M. J. Moore,
Acting Commissioner of Patents.
